UNITED STATES PATENT OFFICE

122,306

DESIGN FOR A COMBINATION SALT AND PEPPER SHAKER

Michael W. Zanghi, Philadelphia, Pa., assignor to Maria Falconi Zanghi, Philadelphia, Pa.

Application May 15, 1940, Serial No. 92,397

Term of patent 7 years

To all whom it may concern:

Be it known that I, Michael W. Zanghi, a citizen of the United States, residing at Philadelphia, in the county of Philadelphia, and State of Philadelphia, have invented a new, original, and ornamental Design for a Combination Salt and Pepper Shaker, of which the following is a specification, reference being had to the accompanying drawing, forming part thereof.

bination salt and pepper shaker, showing my new design;

The caps shown in dotted lines in Fig. 1 have been omitted from Figs. 2 and 3 for the convenience of illustration.

I claim:

The ornamental design for a combination salt and pepper shaker, as shown and described.

MICHAEL W. ZANGHI.
